UNITED STATES PATENT OFFICE.

LEO MAYER, OF BOSTON, MASSACHUSETTS, ASSIGNOR TO HENRY COLE COMPANY, OF BOSTON, MASSACHUSETTS.

ELECTRIC-LAMP SOCKET.

Application filed November 18, 1927. Serial No. 234,204.

My invention relates to electric lamp sockets and particularly to such as are used in connection with automobile lights.

The object of my invention is to produce a switch located within the lamp socket for making and breaking the circuit.

Another object of my invention is to produce a switch located inside the socket, but with the handle, by which it is operated, located outside the socket and means by which the handle may be removed from the switch by a simple movement of the handle.

The invention will be hereinafter considered in detail and specifically claimed. Reference will now be had to the drawing forming a part of this application, wherein there is illustrated a preferred embodiment of my invention, but it is understood that the elements thereof can be varied or changed as for shape, size, or form, and various modifications thereof in detail and in the arrangement of the parts may be made by those skilled in the art, without departing from the spirit of the invention.

Fig. 1 is a sectional view of a lamp socket showing the location of the switch.

Fig. 2 is a section on line 2—2.

Fig. 2^A is the same view as Fig. 2, but with the switch shown in position when the electric current is broken.

Fig. 3 is a section on line 3—3.

Fig. 4 shows a view of a lamp socket, which is supplied with one electrical terminal; the body of the car acting as the other.

Fig. 5 shows a section of a screw threaded lamp that may be used instead of the lamp shown in Fig. 1.

In the drawings:

The casing 10 is provided at one end thereof with a bayonet joint 11 as shown in Fig. 1, or is provided with threads 12 as shown in Fig. 5 to receive a lamp 13 in the usual and well known manner.

The casing 10 is provided with a plug 14 of insulating material and held securely within said casing, and having a tubular member 15 fast therein and angularly arranged in respect to the axis of said casing. The said tubular member 15 is arranged to house the headed portions of plungers 16 and 17 between which is located a spring 18 normally tending to separate them.

A terminal plug 19 of insulating material, secured on the right hand end of said casing 10 and preferably protruding there-

from, is arranged to receive the wires 20 and 21 which enter holes in metallic cylindrical members 22 and 23, one of which 22 has a spring pressed plunger 24 mounted therein.

Interposed between the plugs 14 and 19 there is a rotatable switch member 25 comprising a rectangular block 26 of insulating material, provided with a flat opening 27 through which a metallic ribbon 28 is passed and is bent at its ends 29 and 30 as clearly shown in Figs. 2 and 3. The very extremes of the ends 29 and 30 are slightly raised and out of contact with the block 26 for the purpose which will presently be explained.

The terminal plug 19 is provided with two insulated posts or stops 31 and 32, so arranged with respect to the ribbon 28 that when the block 26 is turned to the right by means of the handle or switch 33 the ribbon 28 will pass over the posts 31 and 32 without the block 26 being stopped. If however it is desired to remove the handle 33 from the block 26 the handle is turned to the left, the ends of the flat ribbon 28 are stopped by the posts 31 and 32 holding the block in place, and the handle is unscrewed and removed from the block 26.

From the above description it will be seen that when the ribbon 28 is in contact with the plungers 17 and 24 there is a complete electrical circuit. The circuit however is easily broken by turning the block 26 an angle of 90 degrees. The insulated sides of the block are then in contact with the plungers and of course the circuit is broken.

Having described my invention, what I claim is:

1. A lamp socket of the class described comprising a casing having means at one end thereof to receive a lamp; a plug fixedly secured in the casing and having a tubular member secured therein, said member being arranged angularly in respect to the axis of said casing, a terminal plug fixedly secured in the other end thereof, and having a tubular member secured therein, a revolving switch member arranged between the said tubular members comprising a rectangular insulating block, having an opening therein, which carries a metallic contact member, whose two ends are bent against the two sides of the block, and means to rotate said block between the two tubular members to make and break the circuit.
2. A lamp socket of the class described

comprising a casing having means at one end thereof to receive a lamp; a plug fixedly secured in the casing and having a tubular member secured therein, said member being arranged angularly in respect to the axis of said casing, a terminal plug fixedly secured in the other end thereof, and having a tubular member secured therein, a revolving switch member arranged between the 5 said tubular members comprising a rectan-

gular insulating block, having an opening therein, which carries a metallic contact member, whose two ends are bent against the two sides of the block, and means to rotate the said block between the two tubular members to make and break the circuit and means to prevent the block from being rotated in a counter clock-wise direction more than 90 degrees. 15

LEO MAYER.
